UNITED STATES PATENT OFFICE.

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING MACHINE.

Application filed February 2, 1922. Serial No. 533,644.

The present invention relates to skiving machines, and more particularly to machines of the Amazeen type for skiving the margins of sheet material, like leather shoe uppers or other stock adapted for use in the manufacture of boots and shoes, but embodies features of more general application the nature of which will appear in the course of the following description and will be particularly 10 pointed out in the claims.

Different margins of the same shoe upper are frequently provided with scarfs of different angle. If it is desired to fold the skived margin, the scarf is usually made comparatively shallow, and terminates usually in a feather edge. If, however, the margin is to be left unfolded, it is preferred to have the scarf very sharp, and terminating in a blunt shoulder at the edge of the upper. If unprovided with a shoulder of this character, the unfolded margin, if on the inside of the shoe, will curl and cause annoyance to the wearer's foot. This is particularly true of shoes the uppers of which are constituted of a plurality of leather pieces sewed together, the margins exposed on the outside of the shoe being folded, and those on the inside, unfolded; the folded margins being provided with wide, shallow, slanted scarfs, and the 20 unfolded margins with narrow scarfs of sharp angle.

So far as known, all Amazeen skiving machines have heretofore been so constructed as to render it impossible to change materially the relative positions of the skiving knife and the feed roll during the operation of the machine. To skive scarfs of different angle with machines of this type, therefore, it is necessary: first, to run the leather through the machine to produce a scarf of one angle; then stop the machine for the purpose of effecting some necessary adjustment; and finally, to run the leather through the machine, as adjusted, to produce a scarf of different angle in another portion of the margin. This procedure is, of course, wasteful of time, and the necessary frequent adjustments are, furthermore, very troublesome. It has, therefore, been customary to employ a plurality of machines, each adjusted to cut a scarf of a particular, desired angle. The uppers are all first run through one machine to produce one scarf in one portion of the margin, and then through another machine

to produce another scarf in another portion 55 of the margin. Though this practice saves some time and avoids troublesome adjustments, it is still objectionable. Various plans have, therefore, been proposed to improve upon this primitive method of procedure. A 60 machine has been constructed, for example, that is provided with two separate and distinct, differently adjusted, skiving instrumentalities conveniently supported upon a single frame, so that the operator may proceed directly from the one instrumentality to the other while still holding the upper in his hands. This does save further time, but the machine is really two machines, and not one. Again, it has been suggested to use a plurality of gages upon the same machine in order that one margin of the upper may be guided by one gage and another by another, the gages being so arranged as to enable the machine to skive scarfs of different width. 65 70 This suggestion does not, however, provide for scarfs of different angle, and the suggested machine is, furthermore, somewhat complex. For one reason or another, the various proposed improvements have not met 75 80 with commercial favor, so that the more primitive method above described of employing a plurality of separate machines is still the standard in the shoe factor.

In the machine of a copending application, 85 Serial No. 319,565, filed August 25, 1919, of which the present application is a continuation in part, provision is made for relatively adjusting, at will, the angular positions of the skiving knife and the feed roll, during the 90 operation of the machine, to a substantial extent sufficient to meet commercial needs, so that the operator, after skiving a scarf of one angle in a portion of the margin of the leather, is enabled quickly to change the angular relation of the knife and the feed roll. Scarfs of different angle may thus be quickly 95 produced in different portions of the margin of the same shoe upper.

Relative adjustment of the skiving knife 100 and the feed roll is not, of course, new; but such adjustment has heretofore usually involved the use of tools, and so could not be effected during the operation of the machine. Nor is it new to effect such adjustment manually, without the aid of tools; provision for manual adjustment, however, has heretofore contemplated very small changes, such as are 105

necessary to compensate for wear of the knife by grinding. It has furthermore been proposed to effect slight treadle-controlled movement of the feed roll for the purpose of varying the character of the edge of the scarf, but this proposal was not intended to effect the angle of the scarf.

The chief object of the present invention is to provide an improved machine of the above-described character that shall afford quick relative angular adjustment between the knife and the feed means of sufficiently large angular extent to effect the skiving of wide and sharp scarfs in the margin of the shoe upper during the operation of the machine.

With this end in view, the invention consists of the improved machine a preferred embodiment of which is hereinafter described, illustrated in the accompanying drawings, 20 and defined in the appended claims.

In the accompanying drawings, Fig. 1 is a fragmentary elevation of a preferred machine constructed in accordance with the present invention, parts being omitted for clearness; and Fig. 2 is a corresponding plan view of the same.

The skiving machine of the present invention is provided with a continuously rotating, disk skiving knife 185 to which a shoe upper or other stock is advanced by a feed roll 95, which may be longitudinally and vertically adjustable, and a feed disk 143, which may be transversely adjustable. The feed disk and the knife are carried by an overhanging arm 22 of the frame 20 of the machine. The feed roll projects forwardly, as shown, beyond the base portion 21 of the frame. The knife is driven direct from a pulley 4 by a belt (not shown), and the feed roll and the feed disk are driven from the knife, as is described more particularly in a copending application, Serial No. 521,239, filed December 9, 1921. The particular driving mechanism will not be further mentioned herein, since it forms no part of the present invention, and other and well known driving mechanisms may be substituted therefor without affecting the invention in any way. The customary gage is omitted from the drawings for clearness.

The knife and the feed roll are relatively adjustable to skive either a wide, slanting scarf or a narrow, sharp scarf, as is illustrated and described more particularly in a copending application, Serial No. 510,710, filed Oct. 27, 1921. To this end, the knife-carrying bracket 170 is angularly adjustable about a rod 164, being provided with oppositely disposed bearings within which the rod 164 is journaled. The knife-carrying bracket is also adjustable transversely of the feed roll 95 by means including a plunger 176, but this is not further described herein, because the specific transverse adjusting means is not an essential part of the present invention.

A further description thereof may be found in the above-described application, Serial No. 319,565. A finger or lug 188 that projects from the knife bracket is yieldingly engaged by a dog 17 through the action of a spring 189 seated in the frame. The spring thus tends to maintain the lug 188 in engagement with an arm 190. By actuating the arm 190, therefore, in opposition to the action of the spring 189, the angular position of the knife bracket 170 and the knife 185 that is mounted thereon may be adjusted.

The arm 190 is actuated by a treadle (not shown), through a treadle rod 191, about the rod 164, to which it is intermediately pivoted at 193. The arm 190 is provided with adjustable stops, shown as threadedly adjustable screws 318 and 320, adapted, respectively, to engage lugs 322 and 324 that are provided upon the frame. The degree of angular movement of the arm 190 and, therefore, of the knife 185, may thus be adjustably limited. Movement of the knife in one direction may be effected by actuation of the treadle rod 191. Movement in the opposite direction, 90 upon release of the treadle (not shown) is effected by the spring 189. The knife adjustment may be effected during the operation of the machine without affecting the operation of either the knife or the feed means. The spring 189 and the driving belt (not shown) for the knife-driving pulley 4 exert a force upon the knife shaft in the same angular direction, each acting to maintain the stop 320 in engagement with the lug 324. The normal operating position of the knife 185 may therefore be adjustably determined by the stop 320.

As the rod 164 about which the knife pivots is out of line with the cutting edge of the knife, the knife moves both angularly and bodily, in response to the operation of the treadle rod 191, and to a greater or lesser extent, as desired, at the will of the operator, so that scarfs of one angle may be provided with a feather edge, and scarfs of another angle with a blunt edge.

The description of many portions of the machine an understanding of which is not essential to an understanding of the present invention has purposely been omitted, and many parts of the machine have purposely not been illustrated, in order not to distract the attention from the features of the essential novelty. Fuller explanation of such portions of the machine will be found in the copending applications referred to above. It will be clear that the features of novelty may be embodied in other machines, and in machines of other types, and that modifications may be made therein by persons skilled in the art, without departing from the spirit and scope of the invention, as defined in the appended claims.

What is claimed as new is:

1. A skiving machine having, in combina-

- tion, a continuously operating knife for skiving the margin of sheet material, means for operating the knife, means for feeding the material to the knife, and treadle-controlled means operable during the operation of the machine for quickly moving the knife angularly to a substantial extent without interfering with the operation of the knife to effect the skiving of scarf's of different angle in the margin of the material.
2. A skiving machine having, in combination, a knife for skiving the margin of sheet material, means for operating the knife, a rotatable feed roll for feeding the material to the knife, and treadle-controlled means operable during the operation of the machine for quickly moving the knife angularly to a substantial extent without interfering with the operation of the knife to effect the skiving of scarf's of different angle in the margin of the material.
3. A skiving machine having, in combination, a frame, a rotatable knife for skiving the margin of sheet material, a feed roll and a feed disk for feeding material to the knife, and a treadle-controlled arm operable during the operation of the machine for angularly moving the knife, without interfering with the operation of the knife and the feed roll, to effect the skiving of scarf's of different angle in the margin of the material, the arm being provided with adjustable stops each adapted to engage the frame to adjustably control the limits of movement of the knife.
4. A machine of the character described having, in combination, a frame, a rod mounted in the frame, a knife frame journaled on the rod having a lug, a knife mounted on the knife frame for skiving the margin of sheet material, means for operating the knife, means for feeding the material to the knife, a spring acting upon the lug to maintain the knife in a normal position, and a treadle-controlled arm for engaging the lug to quickly adjust the position of the knife angularly to a substantial extent without interfering with the operation of the knife to effect the skiving of scarf's of different angle in the margin of the material.
5. A skiving machine having, in combination, a knife for skiving the margin of sheet material, means for feeding the material to the knife, the knife and the feed means being relatively freely movable angularly to a substantial extent at all times during the operation of the machine, means operable during the operation of the machine for quickly relatively moving angularly, between limits, the knife and the feed means, without interfering with the operation of the knife or the feed means, to a sufficiently large angular extent to provide for effecting the skiving of wide slanting and narrow steep scarf's of different angle in the margin of the material.
6. A skiving machine having, in combination, a knife for skiving the margin of sheet material, a feed roll for feeding the material to the knife, means for rotating the feed roll, the knife and the feed roll being relatively freely movable angularly to a substantial extent at all times during the operation of the machine, means operable during the operation of the machine for quickly relatively moving angularly, the knife and the feed roll, without interfering with the operation of the knife or the rotation of the feed roll, to a sufficiently large angular extent to provide for effecting the skiving of wide slanting and narrow steep scarf's of different angle in the margin of the material, and means for adjustably limiting the relative angular movement of the knife and the feed roll.
7. A skiving machine having, in combination, a knife for skiving the margin of sheet material, means for feeding the material to the knife, the knife and the feed means being relatively freely movable angularly to a substantial extent at all times during the operation of the machine, a manually controlled arm operable during the operation of the machine for quickly relatively moving the knife and the feed means angularly, without interfering with the rotation of the knife or the operation of the feed means, to a sufficiently large angular extent to provide for effecting the skiving of wide slanting and narrow steep scarf's of different angle in the margin of the material, and adjustable means adapted to engage the arm to adjustably limit the relative angular movement of the knife and the feed means.
8. A skiving machine having, in combination, a rotatable disk knife for skiving the margin of sheet material, means for rotating the knife, means comprising a feed roll and a feed disk for feeding material to the knife, the knife and the feed means being relatively freely movable angularly to a substantial extent at all times during the operation of the machine, and means operable during the operation of the machine for quickly relatively moving the knife and the feed means angularly, without interfering with the rotation of the knife or the feed roll or the feed disk, to a sufficiently large angular extent to provide for effecting the skiving of wide slanting and narrow steep scarf's of different angle in the margin of the material.
9. A skiving machine having, in combination, a rotatable knife for skiving the margin of sheet material, means for rotating the knife, means for feeding the material to the knife, the knife being freely movable angularly to a substantial extent at all times during the operation of the machine, and means operable during the operation of the machine for quickly moving the knife angularly, with-

out interfering with the rotation of the knife, to a sufficiently large angular extent to provide for effecting the skiving of wide slanting and narrow steep scarf's of different angle in the margin of the material.

10. A skiving machine having, in combination, a rotatable disk knife for skiving the margin of sheet material, means for rotating the knife, means comprising a feed roll and a feed disk for feeding the material to the knife, the knife being freely movable angularly to a substantial extent at all times during the operation of the machine, and treadle-controlled means operable during the operation of the machine for quickly moving the knife angularly, without interfering with the rotation of the knife or the feed disk, to a sufficiently large angular extent to provide for effecting the skiving of wide slanting and narrow steep scarf's of different angle in the margin of the material.

11. A skiving machine having, in combina-

tion, a rotatable disk knife for skiving the margin of sheet material, means for rotating the knife, means comprising a feed roll and a feed disk for feeding the material to the knife, the knife and the feed means being relatively freely movable angularly to a substantial extent at all times during the operation of the machine, and treadle-controlled means operable during the operation of the machine for quickly relatively moving the knife and the feed means angularly, without interfering with the rotation of the knife or the feed roll or the feed disk, to a sufficiently large angular extent to provide for effecting the skiving of wide slanting and narrow steep scarf's of different angle in the margin of the material.

In testimony whereof, I have hereunto subscribed my name this 31st day of January, 1922.

ANDREW R. RIDDERSTROM.
